His Attorney.

UNITED STATES PATENT OFFICE.

ALBREKT K. BENDIXEN, OF SCHENECTADY, NEW YORK.

DESIGN FOR A STICKPIN.

60,889.

Specification for Design.

Patented Apr. 25, 1922.

Application filed December 19, 1921. Serial No. 523,571. Term of patent 14 years.

To all whom it may concern:

Be it known that I, ALBREKT K. BENDIXEN, a subject of the King of Denmark, residing at Schenectady, in the county of Schenectady and State of New York, have invented a new, original, and ornamental Design for Stickpins, of which the following is a specification, reference being had to

the accompanying drawing, forming part thereof.

The figure is a plan view of a stick pin, showing my new design.

I claim:

The ornamental design for a stickpin, as shown.

ALBREKT K. BENDIXEN.
